(57) **CLAIM**

We claim the ornamental design for walking stick with scoop,
as shown and described.

DESCRIPTION

FIG. 1 is a top, front perspective view of a walking stick with
scoop showing my new design;

FIG. 2 is a left side elevational view, the right side being a
mirror image thereof;

FIG. 3 is a rear elevational view thereof;

FIG. 4 is a top plan view thereof; and,

FIG. 5 is a bottom plan view thereof.
